UNITED STATES PATENT OFFICE.

KOBY KOHN, OF NEW YORK, N. Y., ASSIGNOR OF ONE-HALF TO LOUIS A. KSENSKY, OF DENVER, COLORADO.

TELEPHONE APPARATUS.

No. 850,433.

Specification of Letters Patent.

Patented April 16, 1907.

Application filed October 24, 1903. Serial No. 178,431.

To all whom it may concern:

Be it known that I, KOBY KOHN, a citizen of the United States, residing at New York, New York county, New York, have invented, 5 certain new and useful Improvements in Telephone Apparatus, of which the following is a specification.

This invention relates to telephone systems; and the object of the invention is to 10 provide means whereby when one subscriber on a telephone party-line either calls central or receives a call from central all other subscribers on the line will be prevented from cutting in, thereby preventing any 15 other subscriber on the line from overhearing the conversation or any part of it, and thus insuring absolute privacy on the line while in use.

One of the essential features of my invention is that all receivers on the party-line are 20 in open circuits until a subscriber calls or is called, when his receiver-circuit will be closed and all other receiver-circuits on the line be prevented from being closed by the respective subscribers until the calling or called subscriber has finished the conversation and "central" has restored all parts to normal position.

The invention, which may be used with 25 either the local-generator system or the central-energy system for calling, will be fully described hereinafter, reference being had to the accompanying drawings, in which—

Figure 1 is a diagrammatic view illustrating my invention as used in a system employing local generators for calling central. Fig. 2 is a plan view of the armature-resetting devices. Fig. 3 is a perspective view of one of the armature-carrying arms and its 35 magnets. Fig. 4 is a diagrammatic view illustrating my invention as used in conjunction with what is termed the "central-energy" system. Fig. 5 is a diagram showing devices for sending currents over the main line-wires by the operator at central.

It is to be understood that the present invention may be embodied in an apparatus which may form an attachment to telephones at present in use, or it may be a part of the 50 telephone.

Referring now to Fig. 1, I have illustrated diagrammatically the devices employed at central and also those for two stations *a* and *b*. It is to be understood, however, that the

invention may be used with four stations, of 55 which two will be connected to the line-wires the same as *a* and two the same as *b*.

The line-wires are indicated by X and XX, and F is a generator of any known style, one of such generators being at each station, and 60 when the generator is not in use its armature is cut out at F², which may be considered its normal condition.

We will now assume that a person at station *a* wishes to call central. The generator 65 F is operated to close the circuit at F², and current then passes over wire F' to magnet D, wire D', brush D², contact D³, brush D⁴, wire D⁵, brush A', contact A², brush A³, wire A⁴ back to the generator. This current 70 energizes magnet D, which attracts its armature D⁰, pivoted at 2, and thereby brings contact D⁸ into engagement with brushes B² B³ and breaks the local circuit between the generator and magnet D at D² D³, while at the 75 same time brush D⁶ makes electrical contact with D³. The current from the generator F now passes through magnet D to wire D', wire D⁹ to main wire XX. It did not follow this path before, because the complete outside 80 circuit was interrupted at D⁶, which is connected to main wire X by the wire D⁷. The current passes from wire XX to wire H', magnet H² at central, wire H³, spring contact H⁴, contact H⁵, wire H⁶, brush H⁷, contact H⁸, brush H⁹, wire H¹⁰, wire X, wire D⁷, brush D⁶, contact D³, brush D⁴, wire D⁵, brush A', contact A², brush A³, wire A⁴ to the 85 generator. This current will energize magnet H² at central, and its armature H¹¹, pivoted at 6, will be attracted, with the result that the drop H²⁷ will be released and central be notified of the call. The movement 90 of the armature H¹¹ will cause contact H²⁶ to be engaged by brushes H¹³ and H¹⁵ and contact H²⁵ to be engaged by brushes H¹⁷, H¹⁹, and H²¹, which will establish a circuit for a 95 current from a source of electrical supply, as a battery H²³, as follows: from H²³ to wire H²², brush H²¹, contact H²⁵, brushes H¹⁷ and 100 H¹⁹, wires H¹⁸ and H²⁰ to main line-wires XX and X, respectively. It is now necessary to refer to magnets A, one of which is provided at each station. The magnet A at station *a* receives its current from wire X through 105 wire A⁵, brush A⁶, contact A⁷, brush A⁸, wire A⁹ to magnet A, thence to wire A¹⁰ to the ground to wire H¹⁴ at central, to brush H¹³,

brush H¹⁵, contact H²⁶, brushes H¹⁷ and H¹⁹, wires H¹⁸ and H²⁰ to main line-wires XX and X, respectively. It is now necessary to refer to magnets A, one of which is provided at each station. The magnet A at station *a* receives its current from wire X through 105 wire A⁵, brush A⁶, contact A⁷, brush A⁸, wire A⁹ to magnet A, thence to wire A¹⁰ to the ground to wire H¹⁴ at central, to brush H¹³,

contact H^{20} , brush H^{15} , wire H^{16} , to battery H^{23} . At station b the magnet A receives its current from wire XX, and if two other stations be on the line the magnet A at one will 5 take its current from wire X and the other from wire XX. Thus when current is sent from battery H^{23} over wires X and XX the magnets A at all the stations will be energized and attract their armatures A^0 , which 10 are pivoted at 4.

Some of the current passing over wire H^{18} from the battery H^{23} will pass from wire H^{18} to magnet H^2 , wire H^3 , spring-contact H^4 , contact H^5 , and wire H^{24} to battery H^{23} , and 15 this current will energize the magnet H^2 and keep the circuits closed between the battery H^{23} and wires X and XX after the current from the generator F, which first energized the magnet H^2 , has ceased.

20 When the armatures A^0 are attracted, the contacts A^2 move out of engagement with their respective brushes A' A^3 , and the circuits from generators F to magnet H^2 are all broken at this point. This will prevent any 25 other station on the line from calling up central until after all parts have been restored to normal position. The attraction of the armatures A^0 also results in breaking the circuit from battery H^{23} through magnet A at 30 A^6 , A^7 , and A^8 , and the resistance of the magnet A is therefore eliminated. When the generator F at station a was operated, the attraction of armature D^0 caused the brushes B^2 B^3 to become engaged with contact D^8 , 35 which resulted in closing a circuit from wire X to wire B' , brush B^2 , contact D^8 , brush B^3 , wire B^4 , magnet B, wire B^5 , brush B^6 , contact B^7 , brush B^8 , wire B^9 to earth and back to battery H^{23} . Current will therefore flow 40 over this circuit and energize magnet B, and its armature B^0 , pivoted at 3, will be attracted and cause the contact G^4 to engage brushes G^2 and G^3 , and thereby complete a metallic circuit for the receiver G, as follows: from wire 45 X to wire G' , brush G^3 , contact G^4 , brush G^2 , wire G^5 , receiver G, wire G^6 to wire XX, and communication is then established 50 between central and station a . At the same time the receiver-circuit is closed the contact B^{12} engages brushes B^{10} and B^{11} , and thereby establishes another generator-circuit in place of the one broken at A' A^2 A^3 and which will enable the speaker at station a to ring off. This circuit is as follows: from generator 55 F to wire F' , magnet D, wire D' , wire D^0 , wire XX, wire H' , magnet H^2 , wire H^3 , spring-contact H^4 , contact H^5 , wire H^6 , brush H^7 , contact H^8 , brush H^9 , wire H^{10} , wire X, wire D^7 , brush D^6 , contact D^3 , brush 60 D^4 , wire D^5 , wire B^{14} , brush B^{10} , contact B^{12} , brush B^{11} , wire B^{13} , wire A^4 to generator. As only one magnet D on the line—viz., that at station a —was energized, it follows that only at this station can the receiver G be cut 65 into circuit and the last-described generator-

circuit be established, and no other person on the line can interfere with or overhear the conversation between the person at a and the person with whom the conversation is being carried on.

When magnet B attracted its armature and closed the receiver-circuit and the generator-circuit, its own circuit was broken at B^6 , B^7 , and B^8 .

When central answers the call from the 75 person at station a , a jack or plug is inserted in H^{28} , which will force the contact-spring H^4 away from H^5 , thereby breaking the circuit from the battery H^{23} and deenergizing the magnet H^2 , which will release its armature, and the latter will be restored to normal position by the spring H^{12} . The drop H^{27} may also be restored to its normal position, and then the operator at central may withdraw the jack from H^{28} and permit the 80 spring-contact H^4 to engage H^5 , and then the circuit from the generator F at station a will be complete to enable the person using the phone at such station to ring off.

We will now assume that central desires to 90 call up station b . A current will first be sent over lines X and XX to energize all the magnets A and cause them to attract their armatures A^0 , and thereby cause the contact E^{16} to engage brushes E^2 and E^3 , and thereby 95 establish a circuit at each station from one or the other of wires XX or X to wire E' , brush E^2 , contact E^{16} , brush E^3 , magnet E, wire E^4 , brush E^5 , contact E^6 , brush E^7 , wire E^8 , magnet C, wire C' , bell C^2 , wire C^3 , wire C^4 to the earth to central and then to the respective wires X or XX. As before stated, it is intended to have four stations on the same line, and the bell C^2 at two of the stations will be connected to the wire X and at 100 the other two stations to the wire XX. As shown at station a , the bell is connected to wire X and at station b to wire XX, and we will assume that at station c the connection is the same as at a and at d the same as at b . Now when central desires to call a station—say b —it is not desirable to ring up d ; but as the current sent from central over wire XX will pass through the bell C^2 at each of these stations one of the bells—say that at b —will be 105 polarized to respond to a — current and the one at d to a + current only. Now when the operator at central desires to call b a — current will be sent over wire XX, which will ring the bell at b , but not at d .

It will be observed that the armature B^0 is common to both magnets B and C, and as the — current sent out from central to station b will pass through magnet C at this station the end of armature B^0 adjacent to C is in 115 the form of a permanent magnet with a polarity opposite to that of the current in order that C may attract it. When, therefore, the current is sent from central over wire XX to b , the bell C^2 at this station will 120

ring and the magnet C will attract the armature B^0 , and thereby close the receiver-circuit at G^2 , G^3 , and G^4 and the generator-circuit at B^{10} , B^{11} , and B^{12} , and central can then talk with a person at station b or put him into communication with some other person who may wish to talk to him, either on the same line or another. As shown, the magnets E and C are in series with the bell C^2 , and the current used for operating the bell C^2 is a continuous vibratory current, which in itself is not new; but the use of such a current for operating a magnet to cut in the receiver and also accomplish the making and breaking of local circuits is an important feature of my invention.

It will be observed that the armature E^0 of the magnet E is held retracted by a spring E^{17} and that the armatures for magnets A, B, C, and D have no springs. The function of the magnet E is to reset the armatures of the magnets A, B, C, and D after they have been attracted, and the spring E^{17} is of sufficient strength to prevent the armature E^0 being attracted when the current for operating the bell C^2 is passing through magnet E, it requiring a stronger current to attract the armature E^0 than it does to ring the bell C^2 .

Assuming now that the armatures A^0 , B^0 , and D^0 have been attracted by their magnets and it is desired to restore them, the operator at central will send a current over wires X and XX of the necessary strength to attract the armature E^0 . Before describing the effect of this current it is necessary to refer to Fig. 2, which shows in plan view the relative positions of the armatures A^0 , B^0 , D^0 , and E^0 and the magnets A, B, C, D, and E, and it will be seen that the arm which carries the armature E^0 is pivoted at 5 on one side of the magnet E and extends for some distance on the opposite side of the magnet E. The arms which carry the armatures D^0 , A^0 , and B^0 are respectively pivoted at 2, 4, 45 and 3 and extend under an enlargement 7 on the end of the arm carrying the armature E^0 . These arms are to be so arranged that when the armatures A^0 , B^0 , and D^0 , or either of them, have been attracted by their respective magnets their arms will engage the enlargement 7 when the armature E^0 is in its normal or retracted position. If now the armature E^0 be attracted, its arm will press against the arms of such other armatures as have been attracted and rock them on their pivots, and thereby disengage their armatures from their respective magnets. The particular arrangement illustrated is typical only, and the relative positions of the arms may be varied, it being essential only that the arm carrying the armature E^0 shall in some manner engage the other arms and move them to disengage the armatures from their respective magnets.

65 Returning now to Fig. 1, it is to be under-

stood that the armature A^0 at all the stations has been attracted by the respective magnets A, and consequently the contact E^{16} has engaged the brushes E^2 and E^3 at each station. Current will then pass from the wires X and XX, respectively, to wire E', brush E^2 , contact E^{16} , brush E^3 , magnet E, wire E^4 , brush E^5 , contact E^6 , brush E^7 , wire E^8 , magnet C, bell C^2 , wire C^3 , wire C^4 to earth and back to central. The effect of this current will be to energize the magnet E, and its armature will at once begin to move. The current will also affect momentarily such magnets as may have been cut into circuit with the line-wires X and XX by a call either to or from central and also the magnets C, aiding those of opposite polarity to the current to attract their armatures B^0 and causing those of like polarity to repel their armatures. As the armature E^0 moves all arms engaged with it will also move, with the result that contact will be broken between the brushes E^2 and E^3 and contact E^{16} ; between the brushes B^2 and B^3 and contact D^8 , assuming such contact has been made; between brushes G^2 , G^3 , and contact G^4 ; brushes B^{10} , B^{11} , and contact B^{12} , and this will cut out the receiver and magnets D and B from the wires X and XX and eliminate their resistances to the current. Before the brushes E^2 and E^3 are entirely disengaged from contact E^{16} contact E^{11} on armature E^0 will have engaged the brushes E^9 and E^{10} , and the contact E^6 will engage brushes E^{13} , E^{14} before it is entirely disengaged from brushes E^5 and E^7 , and there is therefore no interruption to the flow of current from wires X and XX through the magnets E to the earth. When, however, the brushes E^5 and E^7 are disengaged from contact E^6 , the magnet C and bell C^2 will be cut out and their resistances eliminated, thereby enabling the full strength of the current to be used for completing the stroke of armature E^0 , with the exception of such as may flow through magnets A and which will not be sufficient to affect the movement of armature E^0 . When the bell C^2 and magnet C are cut out, the current will be from wire E' to brush E^9 , contact E^{11} , brush E^{10} , magnet E, wire E^4 , brush E^5 , loop E^{12} , brush E^{13} , contact E^6 , brush E^{14} , wire E^{15} , wire C^4 to earth. After E^0 has made its full stroke the current is then discontinued at central, spring E^{17} will retract E^0 , and all the parts will be in normal position.

In Fig. 3 I have shown a side view of the arm-carrying armatures B^0 . The armature for magnet C is polarized and is insulated from the armature for magnet B, as indicated at B^{25} in Fig. 1.

It is desirable to provide some means for informing a person desiring to call when the line is busy that such is the fact, and I preferably employ an audible signal for this purpose, which is operated by a current from the

generator F. As before stated, when a call is sent to central or from central all the magnets A on the line are energized and attract their armatures, which results in breaking all the generator-circuits at A¹, A², and A³ and causing contacts K⁷ to engage brushes K⁶ and K⁸. If now a person at some other station should operate the generator F at such station, a current would be generated and flow from the generator over wire F' to wire K¹⁰, bell K, wire K⁹, brush K⁸, contact K⁷, brush K⁶, wire K⁵, brush K⁴, contact K³, brush K², wire K¹, wire A⁴ to generator. This will cause bell K to ring, and thus notify the person that the line is busy.

Preferably the enlargement 7 of the arm carrying armature E⁰ will be provided with adjustable screws (indicated by 9) to engage the arms carrying the other armatures.

It may be stated here that it is not desirable that the current which is sent out from central, either by the operation of magnet H² when a subscriber calls central or by central before calling a subscriber to energize magnets A and B, should operate magnets E or C or bell C², which it would do if of sufficient strength. To prevent this, if the resistance for A is one thousand ohms, (for illustration,) magnet E is provided with one thousand ohms resistance and magnet C and bell C² each with the same resistance, and the current referred to is not of sufficient strength to overcome these combined resistances and at the same time operate either E, C, or C², while it will be quite sufficient to operate A or B. The continuous vibratory current to operate C and C² may be, say, about three times as strong as the current for A and B; but even this will not cause E to attract its armature on account of the resistance offered by spring E¹⁷. The resetting-current must be still stronger, as it must be sufficient to cause the magnet E to overcome the resistance of spring E¹⁷ and attract the armature E⁰.

Various means may be devised for sending the necessary currents over the wires X and XX to the stations a, b, c, and d by the operator at central, and in Fig. 5 I have shown apparatus which may be used for this purpose. Thus for sending the strongest current over the wires X and XX for energizing the magnets E, I provide a battery or other source of electrical supply S of the necessary capacity and provide a switch-lever S', having contacts S² and T, insulated from each other. Brushes S³ and S⁴, adapted to be engaged by the contact S², are respectively connected to wires XX and X. One pole of the battery S is electrically connected by a wire S⁵ to the contact S² and the other pole to the ground. When the switch-lever S' is moved to engage contact S² with brushes S³ and S⁴, current from the battery will be sent over both line-wires XX and X through magnets E to the ground, as already described,

and back to battery S. A portion of the same battery S may be utilized for energizing magnets A, which do not require so strong a current as magnets E. Thus the contact T is electrically connected by a wire T' with a portion only of the battery, as shown in Fig. 5. Two brushes T² and T³, adapted to be engaged by contact T, are respectively connected to wires XX and X, and when switch-lever S' is moved to engage contact T with brushes T² and T³ current from a portion of battery S will flow over wires XX and X through magnets A to the ground and back to the battery S'.

The current for energizing magnets C and bells C² is preferably a continuous vibratory current, and in Fig. 5 I have shown one means for sending a current of this character over the lines X and XX. Thus the line X is connected to a pivoted switch O by a wire O', and the line XX is connected to a similar switch O² by a wire O³. A battery or other suitable generator O⁴ is provided, and the positive pole thereof is connected to a contact O⁵, adapted to be engaged by either of the switches O or O², and its negative pole is connected to a contact O⁶, adapted to be engaged by either of the switches O or O². A commutator is provided in each connection between said contacts and the battery, and the latter is connected to the earth. If the switch O be rocked to engage O⁶, a negative current will be sent over line X through magnets C and return by the ground to battery O⁴. If switch O engages O⁵, a positive current will be sent over line X and return through the ground to battery O⁴. By operating switch O² the same effects take place over wire XX.

One other great advantage possessed by my invention, in addition to the absolute privacy in the use of the party-line by the party using it, is that the bell C², being in series with the magnets C and E, offers so much resistance that the ringing of the bells C² is entirely obviated when a person who has been talking over the line "rings off."

The receiver-circuits are each provided with the usual secondary induction-coil I in close proximity to the usual primary induction-coil J; but these coils form no part of the present invention and are illustrated merely to show that my invention can be applied to telephones now in use without the necessity of mutilating them in any way.

Referring now to Fig. 4, which is a diagrammatic view showing the apparatus at central and that at one station on a party-line in a central-energy system, it will be observed that the magnets A, B, C, D, and E are employed in substantially the same relations as in the system heretofore described. The generator F and its circuits are, however, omitted. In this case the removal of the receiver G from its supporting-hook D¹¹ will

serve to send a signal to central. Assuming now that the receiver G is removed from the hook D¹¹, the latter will be moved by its spring into engagement with a contact D¹⁰ 5 and close a circuit as follows: from hook D¹¹ to contact D¹⁰, wire D¹², brush A³, contact A² on armature A⁰, brush A', wire D¹³, magnet D, wire D¹⁴, main line-wire XX, through battery M², spring-contact M³, contact M⁴, wire M⁵, magnet M, wire M⁶, line-wire X, wire D¹⁵ to hook D¹¹. The closing of 10 this circuit will energize magnets D and M. The magnet D will attract its armature D⁰ and close the circuit for the magnet B at D⁸, 15 B², and B³, and magnet B will be energized and attract its armature B⁰ and close the receiver-circuit at G², G³, and G⁴ and break the local circuit for bell K at K², K³, and K⁴ in the same manner as previously described. 20 The magnet M having been energized will attract its armature M⁰ and cause the contact M⁷ to engage the brushes M⁸ and M⁹ and the contact M¹⁰ to engage brushes M¹¹ and M¹². A circuit will thus be established from 25 battery M² to wire M⁵, magnet M, brush M⁸, contact M⁷, brush M⁹, wire M¹³, to battery M², and the current from the battery will keep magnet M energized to hold its armature attracted and keep circuits closed at M⁷, M⁸, 30 and M⁹ and at M¹⁰, M¹¹, and M¹², so as to absolutely insure the operation of all the magnets A on the party-line and of the magnet B at the station calling. Current can then be sent over both wires X and XX to energize 35 all the magnets A and the magnet B, whose circuit was closed by the action of its coöperating magnet D, in the same manner as previously described in connection with Fig. 1. As soon as the magnets A attract 40 their armatures the circuits for magnets D will be broken at A', A², and A³, and there will thus be no idle resistance in the line during subsequent operations.

As no generator is employed at the stations in the central-energy system, it is necessary to provide some means for ringing the bell K to indicate to a subscriber when the line is busy. As shown, I provide a battery L in the circuit for the bell. When the armature A⁰ is attracted, the contact K⁷ will engage brushes K⁶ and K⁸. An open circuit with a break at D¹⁰ and D¹¹ is then established, including the bell K and battery L, as follows: from hook D¹¹, to wire L', battery 45 L, wire K¹⁰, bell K, wire K⁹, brush K⁸, contact K⁷, brush K⁶, wire K⁵, brush K⁴, contact K³, brush K², wire K¹, wire D¹², and contact D¹⁰. If then the receiver be removed from the hook D¹¹, the circuit will be closed between D¹⁰ and D¹¹ and bell K will ring. 55

It will of course be understood that when the armature B⁰ is operated the contact K³ will be disengaged from the brushes K² and K⁴, and the bell-circuit will thus be broken at 60 this point, and therefore the bell K will not

ring at any station, where armature B⁰ has been operated, when the receiver is removed from hook D¹¹. The same is equally true with reference to Fig. 1, where the generator F will not ring the bell at any station where the armature B⁰ is attracted. In all other respects the apparatus illustrated in Fig. 4 70 will operate in the same manner described with reference to Fig. 1.

Without limiting myself to the details of 75 construction illustrated and described, I claim—

1. In a telephone system for party-lines, the combination of the main-line wires leading from a central office, of a series of telephone-receivers each connected to the line-wires by an open electric circuit, a source of electric-current supply at the central office connected to the line-wires by an open circuit, means including a magnet and an armature, under the control of the user of one receiver for closing this receiver-circuit and for closing said open circuit at the central office for sending current over the line-wires to operate devices for preventing the closure of all 80 the other receiver-circuits, substantially as set forth.

2. In a telephone system for party-lines, the combination of the main-line wires leading from a central office of a series of telephone-receivers each connected to the line-wires by an open electric circuit, a source of electric-current supply at the central office, a magnet and an armature at each receiver-station both connected to one of the line-wires, means under the control of an operator at the central office for sending a current from said source of supply over the line-wires to operate said armatures and magnets at all the receiver-stations to prevent the closure of 95 the receiver-circuits by users thereof, and means under the control of the operator at the central office for subsequently closing each receiver-circuit selectively, substantially as set forth. 100

3. In a telephone system, the combination with the main-line wires, of a series of telephone-receivers each independently connected to said wires by an open electric circuit, a generator adjacent to each receiver, and 115 means operated by each generator for closing its receiver-circuit and preventing the closure of all the other receiver-circuits, substantially as set forth.

4. In a telephone system for party-lines, 120 the combination with the main-line wires of said party-line, of a series of telephone-receivers each independently connected to said wires by an open electric circuit, a generator adjacent each receiver, means operated by 125 each generator for closing its receiver-circuit and preventing the closure of the other receiver-circuits, and a signal which may be operated by the generator at such stations where the receiver-circuits are not closed 130.

when the line is in use, substantially as set forth.

5. In a telephone system for party-lines, the combination with the main wires of the 5 said party-line leading from a central office, of a series of telephone-receivers each independently connected to said wires by an open electric circuit, a generator adjacent to each receiver, means controlled by each generator 10 for sending a current of electricity from a central office over the line-wires, and devices operated by said current for closing the receiver-circuit adjacent to the active generator and for preventing the closure of all the other 15 receiver-circuits, substantially as set forth.
- 15 6. In a telephone system for party-lines, the combination with the main-line wires leading from a central office, of a series of telephone-receivers each independently connect- 20 ed to the line-wires by an open electric circuit, a circuit-closer for each receiver-circuit including an armature, a magnet for each armature, means for energizing each of said magnets selectively to close its receiver-cir- 25 cuit, and means for preventing the closure of all the other receiver-circuits, substantially as set forth.

7. In a telephone system for party-lines, the combination with the main-line wires 30 connected to central, of a plurality of telephone-receivers not exceeding four connected to said wires independently by open electric circuits, a circuit-closer for each circuit including a polarized armature, a magnet for 35 each armature electrically connected to one of the line-wires, and each including in its circuit a polarized bell, two only of said magnets and bells being connected to one line- 40 wire, and the polarities of the two bells being opposite, and the polarities of the armatures coöperating with the magnets being also op- 45 posite, whereby when a current of one polarity is sent over said line-wire it will ring one bell and operate one armature to close its receiver-circuit but will not affect the other bell and armature on the same line-wire, sub- 50 stantially as and for the purpose set forth.

8. In a telephone system for party-lines, the combination with the main-line wires 55 leading from a central office, of a plurality of telephone-receivers each independently connected to said wires by an open electric circuit, a circuit-closer including an armature for each circuit, a magnet B for each armature, a generator F adjacent to each magnet B, means controlled by the generator for es- 60 tablishing electrical connection between a main line-wire, its magnet B and the earth, a magnet A adjacent to each receiver electric- 65 ally connected to one of the main wires and the earth, and devices operated by the mag-

nets A for preventing the closure of all the receiver-circuits except the one to the generator which was operated, substantially as set forth.

65

9. In a telephone system for party-lines, the combination with the main-line wires leading from a central office, of a plurality of telephone-receivers each independently connected to said wires by an open electric circuit, a circuit-closer including an armature for each circuit, a magnet B for each armature, a generator F adjacent to each magnet B, means controlled by the generator for estab- 70 lishing electrical connection between a main-line wire, its magnet B and the earth, a mag- 75 net A adjacent to each receiver electrically connected to one of the main wires and the earth, means controlled by the generator for sending a current over the main wires 80 through all the magnets A and the magnet B adjacent the generator operated, and devices operated by the magnets A for preventing the closure of all the receiver-circuits except the one to the generator which was operated, 85 substantially as set forth.

10. In a telephone system, the combination of a series of magnets and their armatures for making and breaking circuits, said armatures being pivoted and normally tend- 90 ing to remain in any position to which they are moved, a resetting-magnet, and an armature to be operated by the latter magnet and normally in position to be engaged by arms on the other armatures when the latter are 95 operated, and said resetting-armature when attracted by its magnet acting to restore all the other armatures which engage it to normal position, substantially as set forth.

11. In a telephone system, the combination of a series of magnets and their armatures for making and breaking circuits, said armatures being pivoted and normally tend- 100 ing to remain in any position to which they are moved, a resetting-magnet, an armature to be operated by the latter magnet and normally in position to be engaged by arms on the other armatures when the latter are op- 105 erated, and said resetting-armature when at- 110 tracted by its magnet acting to restore all the other armatures which engage it to normal po- 115 sition, and means for restoring the resetting-armature to normal position when released by its magnet, substantially as set forth.

In testimony whereof I have signed my name to this specification in the presence of two subscribing witnesses.

KOBY KOHN.

Witnesses:

GEORGIA P. KRAMER,
JOHN G. HINKEL.
